UNITED STATES PATENT OFFICE.

HENRIK KELSTAD, OF MINNEAPOLIS, MINNESOTA.

TAP.

SPECIFICATION forming part of Letters Patent No. 391,161, dated October 16, 1888.

Application filed June 29, 1888. Serial No. 278,516. (No model.)

To all whom it may concern:

Be it known that I, HENRIK KELSTAD, of Minneapolis, county of Hennepin, and State of Minnesota, have invented certain new and 5 useful Improvements in Taps, of which the following is a specification.

My invention relates to improvements in an implement for cutting threads in an aperture; and it consists, generally, in the combination 10 and arrangement hereinafter described, and particularly pointed out in the claim.

In the drawings which form a part of this specification, Figure 1 is a side elevation of my improved tap. Fig. 2 is a longitudinal 15 section. Fig. 3 is a horizontal section.

In the drawings, 2 represents the body or shank of the tap. The lower extremity is provided with threads 3, and the upper extremity is furnished with a suitable socket, 4, 20 by which the device is turned. The shank 2 is preferably split or divided into two parts, in order that the threaded portion may be thrown outward or spread and cause the cutting portion of the threads to describe a 25 greater or less diameter, as the case may require. A set-screw, 5, may be arranged to pass through one half of the shank 2, in which it is properly screw threaded. The extremity of this set-screw bears against the opposite 30 half of the shank. By turning this set screw in one direction the two halves of the shank are forced apart, thus increasing the diameter or circle described by the cutting-edges of the tap. By turning the set-screw 5 in the 35 opposite direction the pressure between the two halves is released and the spring in the material forming the socket 4, by which the two halves are connected, will be sufficient to cause the halves to be forced back to the original 40 position.

The threaded portion 3 of the tap may be provided with the relief-notches 6 upon two sides, in order to facilitate the working of the device.

45 The operation of the device is as follows: A blank is provided which is sawed or cut through the center lengthwise, and is screw-threaded at the end to give the proper pitch and diameter of thread required. The socket 4 is preferably so formed that the tension of the upper portion of the said socket, which connects the two halves closely together, causes them to assume the form of an ordinary straight tap. The aperture in which the 50 thread is to be cut will be of a size or diameter

60 to receive the tap when closed. The threaded portion will be inserted into the aperture to the depth required for the thread. The set-screw 5 will then be turned to force apart the two halves of the tap. The tap will now be revolved by a suitable handle in the 65 socket 4 in a direction to cut the thread outward toward the surface. When this operation has been carried on sufficiently to finish the first cut, the set-screw 5 may be again turned and the two parts of the tap forced 70 farther apart. The tap is again revolved and another cut made in the aperture, increasing the depth of the thread already started. This operation is kept up until the full depth 75 of the thread has been cut.

A certain amount of spring in the material 80 of which the tap is made is occasioned between the point where the set-screw 5 bears and the lower or free end of the two portions of the 85 thread 3. This is advantageous in the cutting operation, as it avoids a too heavy cut, and thus prevents the thread in the aperture from becoming broken by the action of the tap.

It will be seen that the device will work 90 equally well if the thread is cut by advancing or turning the tap into the aperture in the ordinary manner; but I prefer to place it in the aperture as described previous to the commencement of the cut, for the reason that I am enabled to more accurately gage the cut both in amount and depth by starting it in this way. Another advantage is that in cutting from the bottom upward the chips or cuttings are thrown outward by the action of 95 the tap.

I claim as my invention—

In a device of the class described, the combination, with the shank 2, the lower portion 95 of which is formed in two halves, the upper portion suitably secured together, of the threads 3, cut upon the lower or free ends of the said shank, and the set-screw 5, passing through one part of the shank and bearing 100 upon the other at a point above the threads 3 and operating to force the two halves apart, in the manner substantially as described.

In testimony whereof I have hereunto set my hand this 23d day of June, 1888.

HENRIK KELSTAD.

In presence of—

R. H. SANFORD,
C. L. NACHTRIEB,
